UNITED STATES PATENT OFFICE.

CHARLES E. LOMBARD, OF EAST WILTON, MAINE.

SPINNING AND TWISTING MACHINE.

937,450.

Specification of Letters Patent. Patented Oct. 19, 1909.

Application filed October 18, 1907. Serial No. 398,079.

To all whom it may concern:

Be it known that I, CHARLES E. LOMBARD, a citizen of the United States, residing at East Wilton, in the county of Franklin and State of Maine, have invented certain new and useful Improvements in Spinning and Twisting Machines, of which the following is a specification, reference being had to the accompanying drawings.

10 My invention relates to improvements in spinning and twisting machines.

One object of the invention is to provide an improved mechanism for actuating the fliers to build up the yarn upon the bobbins.

15 Another object of the invention is to provide a tension or brake device for the bobbin spindles.

A further object of the invention is to improve and simplify the construction of machines or apparatus of this character and thereby render the same more durable and efficient and less expensive.

With the above and other objects in view, which will appear as the nature of the invention is better understood, the same consists of the novel features of construction and the combination and arrangement of parts hereinafter described and claimed, and illustrated in the accompanying drawings, 30 in which—

Figure 1 is a side elevation of my improved yarn spinning and twisting machine; Fig. 2 is a top plan view, parts being broken away and in section, of the spinning and twisting mechanism; Fig. 3 is a rear end elevation of the same; Fig. 4 is a detail longitudinal section through one of the twistors or fliers and the co-acting parts; Fig. 5 is a detail side elevation, on an enlarged scale, of 40 portions of the builder mechanism; Fig. 6 is a detail vertical section taken on the plane indicated by the line 6—6 in Fig. 5; and Fig. 7 is a detail vertical section taken on the plane indicated by the line 7—7 in Fig. 5.

45 In the drawings 1 denotes the main frame on which the spinning and twisting mechanism is mounted and 2 denotes a supplemental frame (which may be made a part of the main frame) on which is mounted mechanism for feeding the yarn or roving. The frame or support 2 has arranged within it adjacent to its front or outer end a yarn feed drum 3 against the periphery of which two 50 yarn spools or drums 4, 5 are adapted to bear and to be rotated by reason of their frictional contact with the drum 3. The up-

per supply spool 4 has at its ends pivots or trunnions 6 which bear against the upper edges of the inclined supporting arms 7 projecting from the opposite sides of the frame 60 2. The weight of the spool 4 thus holds it in contact with the feed drum 3. The lower yarn supply spool 5 has at its ends pivots 8 which are removably engaged with hook shaped bearings formed in the lower ends of 65 hanger arms 9 which are carried by a transverse shaft 10 arranged for rocking or oscillatory movement in bearing notches formed in the upper end of the arms or supports 7. Upon one end of the rock shaft 10 is a de- 70 pending crank arm 11 between the lower end of which and the frame 2 is a coil spring 12. The latter swings the arm 11 inwardly and hence actuates the hanger 9 to press the spool 5 against the feed drum 3. 75

The strands of yarn or roving *a* from the upper spool 4 pass through a suitable transverse guide 13 and between an upper set of rolls 14, 15, 16; and they lead to the fliers of the upper set of bobbins as presently explained. The strands of yarn or roving *b* from the supply spool 5 pass through a transverse guide 17 and between a lower set of rolls 18, 19, 20; and they pass to the fliers of the lower set of bobbins. There is no 85 drawing action between the drums 3, 14, 15 and 16 and the drums 18, 19 and 20. The upper rolls 14, 18, of each of the two sets are supported upon the two lower rolls of each set, which lower rolls are geared together by 90 providing an idler pinion 21 which meshes with pinions 22 on the shafts of said lower rolls. On the shafts of the rolls 16, 20, are gears 23, 24, both of which mesh with a gear 25 loosely mounted upon a stub shaft on the 95 frame 2. The gear 24 also meshes with an idler gear 26 which in turn meshes with a gear 27 on the shaft of the feed drum 3. Carried by the gear 25 is a pulley 28 which is connected by a belt 29 to a cone pulley 30 100 loosely arranged on a stub shaft on the frame 2. The cone pulley 30 is connected by a crossed belt 31 to a cone pulley 32 loosely mounted on a stub shaft on the frame 2 and carrying a belt wheel or pulley 33. 105

Arranged upon the upper portion of the main frame 1 are transversely extending upright supports or standards 34, 35, in which are arranged upper and lower sets or horizontal series of spindles 36 which carry upon 110 their outer ends the usual bobbins 37. Co-acting with each of the bobbins is a flier 38

constructed preferably as shown in Fig. 4 and comprising a head 39 rotatably and slidably mounted upon the inner portion of the spindle 36 and provided at its rear end with a tubular extension or shaft 40 and upon its front end with oppositely disposed rods 41 arranged for sliding movement in a grooved pulley 42 which latter is swiveled or mounted for rotation in the standard or upright 34. The outer ends of the rods 41 are connected and one of them carries a hook 43 to receive the yarn or roving.

The fliers of the upper set of bobbins are driven by belts 44 passed around the pulleys 42 and an upper driving drum or roll 45 journaled in an extended front portion of the frame 1. The fliers of the lower set of bobbins are similarly driven by belts 46 arranged between the pulleys 42 and a lower 20 drum or roll 47 journaled in the lower front portion of the frame 1. The shafts of the drums 45, 47, are provided with pulleys 48 which are connected by belts 49 to a double pulley 50 fixed upon a transverse shaft 51, 25 which latter is connected by a train of speed gears 52 to a transverse shaft 53. On one end of the latter is a pinion 54 which meshes with a driving gear 55 on a main drive shaft 60 to which latter power may be applied in 30 any suitable manner.

On the shaft 60 is a pulley 61 which is connected by a belt 62 to the pulley or wheel 33, so that the feeding mechanism upon the frame 2 will be driven from the mechanism 35 upon the frame 1.

The fliers 38 are reciprocated longitudinally of the bobbins for the purpose of building up the yarn thereon, by rack bars 63, which have their forward ends rotatably 40 and non-slidably connected to the fliers, preferably, by providing them with sleeves 64 which are arranged upon the tubular extensions or portions 40 of the flier heads and retained thereon by collars 65. This connection of the forward ends of the rack bars is sufficiently loose to allow their rear ends to have a slight vertical movement. Said rear ends of the bars 63, on the upper edges of which are formed racks, project through 45 a suitable opening in the rear support or upright 35 and also through openings in a transverse guide bar 66 arranged in a movable builder frame or member 67. The latter is preferably mounted for swinging or 50 oscillatory movement at the rear of the main frame 1 and as shown is of substantially U-shape consisting of two depending side plates or arms 68 fixed at their lower ends upon a transverse rock shaft 69 suitably 55 journaled on the frame 1 and having their enlarged upper portions connected by the guide 66 and a cross piece 67^a. The guide 66 holds the rack 63 in mesh with pinions 71 60 on a transverse shaft 72 journaled in bearings in the side plates 68 of the builder. On

one end of the shaft 72 is a worm gear 73 adapted to mesh with a worm 74 on one end of a shaft 75 journaled in suitable bearings on a retractable support 76 which is preferably in the form of a plate pivoted at its 70 lower end as at 77 on one of the arms or side plates 68 and adapted to have its upper end secured to the upper portion of the latter by a clamping screw 78 or an equivalent clamping or securing device. By pivoting 75 the support or plate 76 it will be seen that the worm 74 which it carries may be moved out of mesh with the gear 73 so that the racks 63 may be drawn inwardly in resetting the builder mechanism as hereinafter explained. The shaft 75 is prevented from moving in one direction, preferably, by fixing to it a ratchet wheel 79 which is engaged by a spring actuated pawl or dog 80 pivoted at 81 upon the plate or support 76; 85 and said shaft is rotated in the other direction by the engagement of a gear 82 with a stationary rack 83 arranged upon the main frame and preferably upon the upright or standard 35. The gear 82 is loose upon the 90 upper portion of the shaft 75 but is connected to it for rotation in one direction by a pawl and ratchet device consisting of a ratchet wheel 84 fixed on the shaft and adapted to be engaged by a spring actuated 95 pawl or dog 85 pivoted upon said gear. This pawl and ratchet connection between the gear and the shaft allows the former to turn in one direction without rotating said shaft and hence without actuating the shaft 100 72 and the racks 63, while the last mentioned parts will be actuated when the gear 82 is rotated in the opposite direction.

The rock shaft or pivot 69 for the flier is actuated so as to rock or oscillate the latter 105 by means of a heart shaped cam 86 arranged on the main drive shaft 60 and adapted to have its periphery engaged by an anti-friction roller 87 on a lever 88 suitably pivoted at 89 in the frame 1. The lever 88 has an 110 arm 90 which is connected by a link 91 to a crank arm 92 on the shaft 69.

For the purpose of varying the speed of the bobbin carrying spindles while the yarn is being wound upon different portions of 115 the bobbins I provide a tension or friction brake device for said spindles. This device consists of a friction disk or wheel 93 arranged upon the projecting rear end of each of the spindles 36 and adapted to be engaged 120 by a brake spring 94 arranged upon a slideable operating bar 95. The bar 95 is preferably arranged upon the rear face of the upright 35 between the upper and lower sets of spindles as more clearly shown in Fig. 3, 125 and the springs or resilient brake shoes 94 project upwardly and downwardly from said bar so as to engage the disks 93. The pressure exerted by the springs 94 against the disks is adapted to be regulated by set 130

screws 96 arranged in studs or projections upon said bar and adapted to impinge against said springs as shown. One end of the bar 95 is connected to one arm of a bell 5 crank 96^a pivoted at its angle at 97 on the frame 1 and having its other arm connected by a link 98 to a crank arm 99 on the rock shaft 69.

The operation of the machine is as follows: The spools 4, 5, containing the yarn or roving are properly supported as shown in Fig. 1 and the strands *a b* are passed through the guides and the rolls on the frame 2 and after being engaged with the hooks 43 of the 10 fliers are attached to the bobbins. Power is applied to the main drive shaft 60 and the various parts of the machine receive their motion from said shaft through the gearing above described. The supply spools or 15 drums 4, 5, being pressed, the former by gravity and the latter by the spring 12, against the positively driven drum 3 are rotated by the latter and the strands of yarn *a b* are fed to the guides and the upper and 20 lower sets of rolls as will be readily understood. Owing to the provision of the speed gearing 52 between the main shaft 60 and the shaft 51 from which the rolls 45, 47 are 25 driven, the fliers will be driven at a higher rate of speed than the bobbins and hence the 30 strands of yarn will be thoroughly twisted before being wound upon the bobbins. The heart shaped cam 86 will oscillate the lever 88 and the movement of the latter will be 35 imparted through the intermediate connections to the rock shaft 69 to which the builder frame or member 67 is connected, and hence the latter will be oscillated. This 40 oscillation of the builder causes the rack bars 45 and hence the fliers to be reciprocated; and owing to the engagement of the gear 82 with the stationary rack 83, said gear will be 45 oscillated and when it rotates in one direction the worm shaft 75 will turn with it and will actuate the shaft 72 carrying the pinions 71, consequently said racks will be 50 moved forward a little more than the length of the rocking movement of the builder, and the fliers will be gradually moved longitudinally of the bobbins so that the yarn will be wound evenly upon the bobbins. When the 55 gear 82 rotates in the opposite direction it will turn independent of the worm shaft 75, which latter will be held against rotation by the pawl 80 and the ratchet 79. The movement of the rock shaft 69 is also imparted through the parts 99, 98 and 96 to the bar 95 so that the latter will be reciprocated and 60 will vary the tension of the brake springs 94 upon the brake disks or wheels 93 on the bobbin carrying spindles. The operation of these parts is so regulated that when the 65 yarn is being wound upon the small or tapered part of the bobbins the bar 95 moves outwardly to relieve the tension of the brake

springs upon the brake disks or wheels and when the yarn is being wound upon the larger portions of the bobbins the friction is increased by the movement of said bar in the opposite direction. After the bobbins 70 are full, the screw or fastener 78 is operated to release the plate or support 76 which may then be swung to disengage the worm 74 from the gear 73 so that the racks 63 may be drawn rearwardly and reset. 75

It will be understood that any suitable mechanism other than the one illustrated and described may be used in connection with my improved builder mechanism for feeding the yarns thereto and that the bobbins 80 may be disposed either vertically or horizontally according to the character of the feeding device or mechanism.

While I have shown and described in detail the preferred embodiment of my invention, it will be understood that I do not limit myself to the precise showing set forth and that various changes in the form, proportion and minor details of construction and arrangement of parts may be made without departing from the spirit or sacrificing any of the advantages of my invention. 85

Having thus described my invention what I claim is:

1. The combination of a spindle carrying 95 a bobbin, a flier movable longitudinally of the spindle, a movable builder member, a pinion arranged on the latter, a rack in mesh with said pinion and operatively connected to the flier for reciprocating the same, means 100 for actuating said builder member and means for intermittently rotating said pinion.

2. The combination of a spindle carrying 105 a bobbin, a flier movable longitudinally of the spindle, a movable builder member, a pinion arranged on the latter, a rack in mesh with said pinion and operatively connected to the flier for reciprocating the same, a shaft for the pinion, means for actuating said builder member, a stationary rack, a second 110 shaft operatively connected to the pinion shaft, means for preventing the rotation of the second shaft in one direction, and a gear mounted upon the second shaft to mesh with the stationary rack and connected to said 115 shaft to rotate therewith in one direction but free to turn thereon in the other direction.

3. The combination of a spindle carrying 120 a bobbin, a flier movable longitudinally of the spindle, a movable builder member, a pinion arranged on the latter, a rack in mesh with said pinion and operatively connected to the flier for reciprocating the same, means for actuating the said member, a shaft for the pinion, a second shaft, driving connections between the second shaft and the pinion shaft, means for disconnecting said driving connections, means for preventing the rotation of the second shaft in one direction, 125 a stationary rack, and a pinion arranged on 130

- the second shaft to mesh with the stationary rack and adapted to rotate with said shaft in one direction and to turn freely thereon in the other direction.
- 5 4. The combination of a spindle carrying a bobbin, a flier movable longitudinally of the spindle, a movable builder member, a pinion arranged on the latter, a rack in mesh with said pinion and operatively connected to the flier for reciprocating the same, means for actuating said builder member, a shaft for said pinion, a gear upon said shaft, a retractable support upon the builder member, a second shaft journaled upon said support, a gear on the second shaft to mesh with the one on the pinion shaft, means for preventing the rotation of the second shaft in one direction, a stationary rack, a pinion arranged to mesh with said stationary rack and mounted upon the second shaft for rotation therewith in one direction but free to turn independent thereof in the other direction.
- 10 5. The combination of spindles carrying bobbins, fliers movable longitudinally of said spindles, a swinging builder frame, a guide in the latter, rack bars engaged with the guide and operatively connected with the fliers for reciprocating the same, a shaft in said frame, pinions upon said shaft in mesh with said rack bar, means for oscillating said frame and means for imparting an intermittent movement to said shaft.
- 15 6. The combination of spindles carrying bobbins, fliers movable longitudinally of said spindles, a swinging builder frame, a guide in the latter, rack bars engaged with the guide and operatively connected with the fliers for reciprocating the same, a shaft in said frame, pinions upon said shaft in mesh with said rack bars, a second shaft operatively connected to the first one, means for preventing the rotation of the second shaft in one direction, a stationary rack, and a pinion arranged to mesh with said stationary rack and mounted upon the second shaft for movement therewith in one direction but free to turn independent thereof in the other direction.
- 20 7. The combination of a spindle carrying a bobbin, a flier movable longitudinally of the bobbin, a swinging builder member, a pinion carried by said member, a rack in mesh with said pinion and operatively connected to the flier for reciprocating the same, means for intermittently operating said pinion, and a cam actuated mechanism for oscillating said builder member.
- 25 8. The combination of a spindle carrying a bobbin, a flier movable longitudinally of the bobbin, a movable builder member, a pinion carried by the latter, a rack in mesh with said pinion and operatively connected to the flier for reciprocating the same, means for actuating the builder member, and means for rotating said pinion, the last mentioned means being controlled by the movement of the builder member.
- 30 9. The combination of a spindle carrying a bobbin, a flier movable longitudinally of the spindle, a movable builder member, a pinion carried by the latter, a rack in mesh with said pinion and operatively connected to the flier for reciprocating the same, means for actuating the builder member, and means for rotating said pinion, the last mentioned means being controlled by the movement of the builder member.
- 35 10. The combination of a spindle carrying a bobbin, a flier movable longitudinally of the spindle, a movable builder member, an operative connection between the builder member and flier, whereby the former will reciprocate the latter, a stationary rack, a gear mounted upon the builder member and adapted to mesh with said rack and means for imparting the movement of said gear to said operative connection between the flier and builder member.
- 40 11. The combination of bobbin carrying spindles, brake disks thereon, a slidably mounted rod, brake springs each having one end fixed to said rod and its other end bearing against the periphery of one of said brake disks, set screws carried by said bar and bearing against the intermediate portions of said brake springs for varying the tension of the latter upon said disks, and means for intermittently operating said rod.
- 45 12. The combination of bobbin carrying spindles, brake disks thereon, a slidably mounted rod, brake springs each having one end fixed to said rod and its other end bearing against the periphery of said brake disks, set screws carried by said bar and bearing against the intermediate portions of said brake springs for varying the tension of the latter upon said disks, a bell crank fulcrumed at its angle and having one arm connected to said rod and a cam device operatively connected to the other arm of said bell crank for operating the latter.
- 50 In testimony whereof I hereunto affix my signature in the presence of two witnesses.
